FURNACE WALL STRUCTURE

Michael Liptak, St. Paul, Minn.

Application January 20, 1939, Serial No. 251,955

6 Claims. (Cl. 110—97)

My invention, generally stated, relates to boiler installations and is directed to an improvement in the wall and boiler drum mountings of the furnace wall. Briefly stated, the objects of the invention are the provision of a wall structure that may be rapidly and economically erected, will compensate for expansion in the wall structure, and will be durable under high temperatures. The major feature of the invention is directed to means for supporting the wall superstructure or masonry that directly supports the boiler drums independently of the lower or main wall structure, and which structure includes a novel arrangement affording an efficient gas-tight expansion joint between the main wall and the wall superstructure.

The invention also includes improved features for directly mounting and sealing the boiler drum or drums, the term boiler drum being used to include the drums frequently distinguished as the steam drums and mud drums. These latter noted features are in the nature of an improvement on or modification of the device disclosed and claimed in my prior Patent No. 1,900,019 of March 7, 1933, entitled "Mud drum seal."

In the accompanying drawings which illustrate the commercial embodiment of the invention, like characters indicate like parts throughout the several views.

Referring to the drawings—

Fig. 1 is a side elevation showing a portion of the boiler installation, some parts being broken away;

Fig. 2 is a vertical section taken on the line 2—2 of Fig. 1 showing the parts on a larger scale than in Fig. 1;

Fig. 3 is a fragmentary perspective, some parts being removed, and some parts being in section showing the furnace wall and boiler drum mounting with the drum removed;

Fig. 4 is a detail with parts broken away, some parts removed and with some parts sectioned on the line 4—4 of Fig. 2;

Fig. 5 is a perspective showing one of the so-called anchoring tiles of the wall structure;

Fig. 6 is a perspective showing one of the wall anchors;

Fig. 7 is a fragmentary perspective showing certain of the wall elements and showing a part of one of the wall girders and projecting shelf;

Fig. 8 is a vertical section of the wall taken approximately on the line 8—8 of Fig. 7; and

Fig. 9 is a fragmentary section taken on the line 9—9 of Fig. 3.

Of the metallic parts of the wall structure 55

illustrated in the drawings, the numeral 12 indicates the upright steel columns that support horizontal steel girders 13. The numeral 14 indicates a sheet steel face plate that is reinforced by a lower horizontal angle bar 15 and by an upper horizontal angle bar 16, which latter noted elements are applied in a manner to be herein-after noted.

The lower or main masonry of the wall structure is indicated as an entirety by the numeral 17, and is capped by sill tiles 18. These sill tiles 18 are preferably in length the full width of the wall, but might be shorter than indicated, and are rectangular. At their inner or fire-exposed ends, these tiles 18 have raised rectangular portions 18'.

By reference particularly to Figs. 2, 7 and 8, it will be noted that the girder 13 is extended horizontally above the reduced portion of the tile 18 with its lower portion spaced well above said tile. As a highly important feature, this girder is provided with a projecting shelf 19 in the form of a strong steel plate bolted, riveted or otherwise rigidly secured to the bottom flanges of said girder. Preferably, and as shown, the shelf 19 is rigidly but detachably secured to the lower flanges of the girder 13 by nut-equipped bolts 19a. This shelf 19 projects above the reduced portion of the tile 18, toward the raised head 18' thereof and preferably terminates a little short of said head.

The wall superstructure is mounted on the inwardly projecting portion of the shelf 19 and is supported thereby from the girder 13. The masonry of this superstructure has a base formed by lintel tile 20 having reduced upper portions that directly overlie, but are spaced from the heads 18' of the sill tile 18. These tiles 20 are of rectangular form, are a good deal like the sill tiles 18, and are provided with rectangular, relatively thick or deep portions 20' that directly rest on the shelf 19. The head portions 18' and 20' of the tile 18 and 20 closely overlap on vertical lines and compensate for expansion of the lower portion of the main wall. To insure the gas-tight joint between these overlapping expansion joint-forming portions, a packing 21, preferably of asbestos but of any suitable pliable or yielding material that will resist high temperatures, is packed into the shelf, as shown in Figs. 2, 3, 7 and 8. Here it should be noted that outward of this packing 21 a free air space 22 is formed between the metallic shelf 19 and the underlying portion of the sill tiles. The packing 21 may be extended any desired distance into the air space 22.

The wall superstructure, in addition to the lintel tiles 20, is shown as made up of various other wall-forming tiles of which the numeral 23 indicates fire brick or tile of standard form, and 24 indicates anchoring tiles. These anchoring tiles 24 constitute an important part of the present invention, and they are formed with anchor seats 25. The seats 25 are preferably made T shaped and into these seats are dropped anchoring hooks 26 having T shaped heads and at the end of 10 their stems having down-turned lock lugs 26'. These anchors 26 may be cast metal or otherwise formed. The depending lock lugs 26' are dropped into channels formed by a metal anchor bar 27, see particularly Figs. 2, 7 and 8, that is welded, riveted or otherwise rigidly secured to the webs of the girders 13 and extends longitudinally of said girders. As shown, the anchor bar 27 is secured to the girders 13 by nut-equipped bolts 27'.

The so-called sill tiles or blocks 18 and lintel tiles 20, having reference to their longitudinal dimensions, may be quite appropriately designated as L-shaped; these L-shaped tile may be further described as in reversed spaced relation to form an expandable and contractible expansion joint.

In the drawings the boiler drum, assumed to be a steam drum, is indicated by the numeral 28, and in this preferred arrangement, the outer end of the steam drum is projected beyond the furnace wall through a passage formed in the upper wall structure by annular rings of fire tile or brick. As shown in the drawings, this opening is formed by an inner ring of fire tile 29 and an outer ring of fire brick 30 that form an opening considerably larger than the extended end of the drum. The projected end of the drum is surrounded by an annular casing 31, preferably of sheet steel, that is of substantially the same diameter as the opening in the wall, and hence considerably larger than the drum.

The face plate 14 is also formed with a passage of substantially the same diameter as the casing 31 and through which the outer end of the drum is extended into the casing. The casing is rigidly secured to the face plate 14, preferably and as shown, by an angular iron ring 32 and nut-equipped bolts 33, see particularly Figs. 2, 3 and 8. The lower edge of the face plate 14 is shown as secured by nut-equipped bolts 34 to the depending flange of the lower bar 15; and the horizontal flange of said bar 15 is shown as secured to the upper flange of the girder 13 by nut-equipped bolts 35, see particularly Fig. 3. The upper edge of the face plate 14 is shown as secured, by nut-equipped bolts 36, to the depending flange of the upper face plate reinforcing angle 16, see particularly Fig. 2.

The drum 28 is rigidly supported from the girder 13 by a metallic saddle 28a that is directly seated on said girder. This saddle may take various forms, but in practice will usually be welded to the boiler and connected to the girder 13 by nut-equipped bolts 35' that permit lateral sliding 65 movements of the saddle on the girder.

The outer end of the drum 28, (see particularly Fig. 2), is provided with a man-hole opening 37 that is normally closed, as shown in Fig. 1, by a man-hole cover 38. Adjustably secured in the outer end of the casing 31 is a flexible steel annular diaphragm 39. This diaphragm, as a novel feature, is slidably and adjustably mounted in the outer end of the casing 31, by frictional locking or clamping means that does not require per-

forating of the casing. Preferably this is accomplished by the novel means illustrated and which, as shown, includes an angle iron anchoring ring 40 secured to the outer edge of the diaphragm, by nut-equipped bolts 41, see particularly Fig. 9. The cylindrical flange of this ring 40 is provided with circumferentially spaced set screws 42 which, as shown, have threaded engagement with the nut-like blocks 43 welded to said diaphragm anchoring ring 40. These set screws preferably work freely through passages in the cylindrical flange of the anchoring ring 40 and frictionally engage the interior of the casing 31.

Bolted or otherwise rigidly secured to the inner 15 edge of the annular diaphragm 39 is an annular joint ring 44. The outstanding flange of this joint ring 44, as best shown in Fig. 9, is secured to said diaphragm by nut-equipped bolts 45. The inwardly projecting annular flange of the joint 20 ring 44 engages tightly against the end of the drum surrounding its man-hole opening 37, and is circumferentially grooved to hold a tightly compressed packing 46 of asbestos or like material which is heat resisting and will form a gas and 25 water-tight joint between the joint ring and the drum.

A packing 47 is placed in the space between the web of the girder 13 and the adjacent face of the wall of the superstructure; and a similar packing 48 is placed in the space between the drum, the tile 29-30, the casing 31 and the diaphragm 39. The interior of the joint flange 44 has an outward conical flare so that it will freely shed or deflect water.

35 Preferably the heads of the bolts 41 are welded to the anchoring ring 40 so that they act as projecting studs. Also, preferably the heads of the nut-equipped bolts 45 are welded to the diaphragm 39 so that they act as projecting studs.

40 With the structure above described, it is evident that the main or lower wall structure may be repaired or, for that matter, completely replaced without disturbing the wall superstructure and boiler drum setting, which latter is supported entirely directly from the girder shelf 19 and the girder itself. Expansion and contraction of the upper and lower wall sections will be compensated for by the vertical movements of the overlapping sill and lintel tiles or blocks 19 and 20 respectively, and the gas-tight joint will be maintained by the packing 21. As the wall superstructure is carried by the girder shelf, this part of the wall will remain a permanent gas and air tight wall for life of the boiler, but can be readily removed or rebuilt if necessary. The anchors 26 anchor the upper or super wall structure to the girder, and the packing 47 insulates and protects the girder from the heat conducted by the super wall structure. Also, this packing 47 and the relative arrangement of shelf and super wall structure prevents upward movement of air and gas between the girder and the super wall structure. When the air space 22 is formed between the shelf 19 and the sill blocks, movement of air to cool or prevent overheating of the shelf is permitted. The insulating packing 48 protects the extended or outer end of the boiler drum from radiation of heat into the atmosphere from the outer end of the drum.

70 The importance of a gas and fluid-tight joint between the outer end of the drum and the joint ring or that portion of the diaphragm that abuts the end of the drum, has already been noted and 75 stated as accomplished by the packing 46 placed

in the grooved edge of the joint ring. In applying the diaphragm the anchoring ring 40 will be so adjusted that when the diaphragm is applied thereto with the packing 46 of the joint ring 44 tightly pressed against the end of the boiler drum, said diaphragm will be under such spring tension that if the boiler contracts axially, the joint ring will follow the drum and maintain the packing 46 tightly against the end of the drum. Also, the adjustment will then be such that if the boiler drum should expand axially, the diaphragm will yield and simply keep the packing 46 more tightly pressed against the drum head.

From the above it will be understood that the diaphragm 39 will be applied to the anchoring ring 40 after the latter has been firmly set by tightening of the set screws 42. The use of these frictional devices, to wit, the set screws 42, or the like, eliminates the necessity for forming holes or seats in the casing 31 and affords an infinitesimally small and accurate adjustment throughout a long range of possible adjustment of the anchoring ring in the casing.

In many instances illustrated, nut-equipped bolts have been shown where spot welding or rivets might be employed; however, it is important that nut-equipped bolts with their heads welded or otherwise rigidly secured in the one instance to the flange of the anchoring ring 40 serving as studs will be employed to facilitate the application of the nuts from the outer side of the diaphragm.

The word "tile" has been herein used in a broad sense to cover either what is referred to in the trade as "fire-brick" or "fire-tile."

What I claim is:

1. In a wall structure of the kind described, a lower main wall capped by sill tiles, a girder

extended above said sill tiles and having a projecting shelf spaced vertically from said sill tiles, lintel tiles carried by said shelf, said sill and lintel tiles having overlapping vertically extended portions affording an expansion joint, a super wall structure built upon and including said lintel tiles, a boiler drum extended through said wall and supported on said girder and projecting outward beyond the latter, a casing supported by said girder and surrounding the outer end of said drum with clearance, and a diaphragm secured in the outer end of said casing and adapted to hold insulating packing against the outer end of said drum.

2. The structure defined in claim 1 in which said drum is directly supported from said girder by an interposed saddle.

3. The structure defined in claim 1 in which said diaphragm is secured in said casing for lateral adjustments toward and from the outer end of said drum.

4. The structure defined in claim 1 in which said girder is an I-beam provided at the intermediate portion of its web with an anchoring flange, and in further combination with metallic anchors interlocked to said anchoring flange and seated in certain of the elements of said super wall structure.

5. The structure defined in claim 1 in further combination with a face plate rigidly secured to the upper flange of said girder and to the inner end of said casing and having an opening through which said drum is passed with clearance.

6. The structure defined in claim 1 in further combination with metallic anchors interlocked to the web of said girder and to certain of the elements of said super wall structure.

MICHAEL LIPTAK.
